UNITED STATES PATENT OFFICE.

EDWARD L. LOVEJOY, OF CAMBRIDGE, NEW YORK, ASSIGNOR TO EDGAR J. LOOMIS AND JOHN L. HUNT, OF SAME PLACE.

DESIGN FOR A BROOM-HOLDER.

SPECIFICATION forming part of Design No. 25,176, dated February 18, 1896.

Application filed January 21, 1896. Serial No. 573,418. Term of patent 14 years.

To all whom it may concern:

Be it known that I, EDWARD L. LOVEJOY, a citizen of the United States, residing at Cambridge, in the county of Washington and State of New York, have invented and produced a new and original Design for Broom-Holders and Similar Articles, of which the following is a specification, reference being had to the accompanying drawings.

The leading feature of my design consists in a surface with projecting sides, one side of which in general contour is vertical and the other side inclined, forming an irregular outline to the whole when viewed in elevation.

A is the central portion of the holder, which, when viewed in elevation, appears to be depressed backward from the sides B and C. These sides extend forward from the central portion of the holder, and the outer contour of one is vertical and that of the other inclined. The circular outline of a roller D extends in part outward from the inner edge 25 of the inclined side C. The inclined projecting side C has a narrow raised surface or rib c extending in an inclined line in harmony with the outline of the side C itself, and the reverse side of the holder has a corresponding 30 raised surface or rib c' formed on the back of the side C opposite to and parallel with the rib c on the front portion of this inclined side C. These ribs are minor details, however, and do not affect the general contour of the 35 holder.

What I claim is—

The design for a broom-holder, and similar articles, substantially as shown and set forth.

In witness whereof I affix my signature in 40 presence of two witnesses.

EDWARD L. LOVEJOY.
